(57) **CLAIM**

The ornamental designs for a combined cord lock and stake, as shown and described.

DESCRIPTION

FIG. 1 is a top, front and right side isometric view of a first embodiment of a combined cord lock and stake embodying my new design, the top, front and left side isometric view being a mirror image thereof;

FIG. 2 is a top, rear and right side isometric view thereof, the top, rear and left side isometric view being a mirror image thereof;

FIG. 3 is a front view thereof;

FIG. 4 is a top view thereof;

FIG. 5 is a left side view thereof;

FIG. 6 is a right side view thereof;

FIG. 7 is a rear view thereof;

FIG. 8 is a bottom view thereof;

FIG. 9 is a top, front and right side isometric view of a second embodiment of a combined cord lock and stake embodying my new design, the top, front and left side isometric view being a mirror image thereof;

FIG. 10 is a top, rear and right side isometric view thereof, the top, rear and left side isometric view being a mirror image thereof;

FIG. 11 is a front view thereof;

FIG. 12 is a top view thereof;

FIG. 13 is a left side view thereof;

FIG. 14 is a right side view thereof;

FIG. 15 is a rear view thereof; and,

FIG. 16 is a bottom view thereof.

The broken lines shown represent unclaimed subject matter and form no part of the claimed design.

1 Claim, 8 Drawing Sheets
